JULIUS H. GILLIS, OF ELIZABETH, NEW JERSEY, ASSIGNEE, BY MESNE ASSIGNMENTS,
TO ANACONDA SALES COMPANY, A CORPORATION OF DELAWARE.

PROCESS AND APPARATUS FOR MANUFACTURING ROOFING ELEMENTS.

Application filed November 21, 1923. Serial No. 678,117.

To all whom it may concern:

Be it known that I, JULIUS H. GILLIS, a citizen of the United States, residing at Elizabeth, in the county of Union, State of New Jersey, have invented certain new and useful Improvements in Processes and Apparatus for Manufacturing Roofing Elements; and I do hereby declare the following to be a full, clear, and exact description of the invention, such as will enable others skilled in the art to which it appertains to make and use the same.

This invention relates to an electrolytic process and apparatus particularly adapted for the plating of non-metallic articles, especially those which are to receive a plating over a portion only of their surfaces. This process and apparatus is peculiarly advantageous in the production of composite roofing elements consisting of a base of various compositions such as the so-called asphalt roofing, and a protective metal layer applied to the surface of the base. Such composite elements may be made conveniently by applying the metallic coating by electrolytic processes, and this invention will be hereafter described in connection with the manufacture of such elements by electrodeposition, although the principles of the invention may be put into practice in the manufacture of articles other than roofing elements.

The roofing elements above referred to are made of many different materials of which the so-called asphalt compositions are perhaps the commonest example and that term will be used hereafter to designate such base materials, although it is intended to include various other materials such as cork, wood fibre, asbestos products, and the like, bound together by suitable binders. These elements are produced for commercial purposes in a number of varying forms such as single or multiple shingles, tiles, strips, boards and the like, and ordinarily the protective layer which is preferably made of a non-corrodible metal such as copper, is applied only to that portion of the base surface which is exposed when the elements are laid on the roof. Since the composition base does not ordinarily have an electrical conducting sur-

face it is necessary to apply a coating upon which the metal may be deposited, and this coating frequently takes the form of powdered graphite applied to the base and held in place by an adhesive. The bases so treated are then placed in electrolytic tanks containing copper anodes and a suitable electrolyte, and the metal is deposited over the desired area in the usual manner. Since the elements are to be produced in large quantities it is desirable to provide a process and apparatus by which a deposit of uniform thickness and quality may be cheaply made and such apparatus should be capable of convenient and efficient operation so that the production of the elements may be carried on without interruption.

In my co-pending application, Ser. No. 661,972, filed September 10, 1923, I have described a process and apparatus for the production of these electroplated elements. In that process the tanks used consist of a plurality of cells which are formed by suitable partitions in the main tank. These partitions are preferably disposed in an inclined position and an element or base is placed on the inclined side wall of each partition on a suitable support and held there during the deposition by means of an anode which is swung to lie parallel with but spaced from the element. Between the anode and the element is a spacer or separator member and on the surface of this separator there is a conducting sheet or suitable contacts so that the plating current by which the metal is deposited on the base may be withdrawn therefrom. In the particular apparatus described in the application referred to, two tanks containing a series of cells are located side by side with a conveyor, there illustrated in the form of a car running on a track, between them. As the process is carried on the car is moved slowly along between the tanks and in its movement it engages the inclined anodes successively and swings them free from the base, the separator members being attached to the anodes so as to move with them. As each anode is swung clear the operator, who is sitting on the car, removes the plated element and places an unplated element in position on

the support. He then swings the anode and separator back to plating position and the deposition begins.

In that apparatus the separator is described as formed of a plate of insulating material such as wood or insulated metal, having contact areas on one face. These areas may be in the form of contacts which are exposed in the face of the separator or else the entire face may be covered with a sheet of conducting material. The separator has its lower edge provided with cut-outs or indentations which serve to define the outline of the deposit. The separator there illustrated is satisfactory for ordinary purposes but it has been found that in use a slight deposit of the metal will build up at the edge of the contacts and eventually form "trees" which build up in the direction of the anode and may eventually serve to short circuit the cell. It therefore becomes necessary periodically to dismantle the anode, remove the separator from it and clean off the built up deposit.

In the present invention I have devised an improved form of separator arranged so that it is reversible. This member has contact areas formed on either face and when a deposit has been built up along the edge in the manner above described, the separator is reversed and this deposit is depleted. It thus becomes unnecessary to subject the separator to a cleaning operation since the reversal itself performs the same function. The new form of separator has various other features of advantage which will appear from a description of the manner in which it is to be used, and in the process of plating with the apparatus here described the manufacture of the elements is considerably simplified while equally good results are obtained.

In the accompanying drawings I have illustrated that embodiment of the invention which is now preferred and in these drawings,

Fig. 1 is a face view of a base or element without the plating.

Fig. 2 is a face view of the new form of separator,

Fig. 3 is a top view of the separator,

Fig. 4 is an end view of the separator,

Fig. 5 is a cross-sectional view on the line 5—5 of Fig. 2,

Fig. 6 is a face view of the anode showing weights in place theron,

Fig. 7 is a top view of this anode,

Fig. 8 is an end view of the anode,

Fig. 9 is a cross-sectional view through one compartment of the electrolytic tank, showing a base in place therein,

Fig. 10 is a longitudinal, vertical, cross-sectional view through a compartment of the tank, showing the anode, separator and element in plating position,

Fig. 11 is a view of the element showing the metal coating deposited thereon, and

Fig. 12 is a view similar to Fig. 10 but showing a modified form of assembly.

In these drawings the base blank 13 is of the form used for a three-unit shingle. This base is of rectangular form, having a length equivalent to three single shingles laid side by side, and along that edge of the element which will be exposed when it is laid in place on the roof are cut-outs 14. When the elements are laid in courses the overlying course will conceal the ends of the cut-outs in the course next below so that each course will appear to be made up of single shingles spaced apart by the width of the cut-outs. The roof made of these elements, therefore, has the ordinary appearance of the wooden shingled roof.

Inasmuch as it is necessary to provide a protective metal layer only over that portion of the element which will be exposed when it is laid, the deposit does not cover the entire face of the element but covers an area which has a width slightly longer than the depth of the cut-outs. Also, since the cut-outs of the course above will expose portions of the element somewhat behind the main body of the layer, it is desirable to provide extending tongues 15 shown in Fig. 11 which are so located as to underlie the cut-outs of the course next above. With this arrangement it will be seen that all exposed portions of the elements are protected by metal and at the same time this metal is not applied to any portion which is concealed. The elements, when laid, therefore, will give the roof the appearance of a metal roof, while only sufficient metal necessary for this purpose is employed.

Referring to Figs. 9 and 10, it will be seen that the electrolytic tank consists of bottom, side and end walls 16 which may be made of slate or wood, provided with a protective sheathing. Any material which is capable of withstanding the action of the electrolyte may be used for this purpose, although the sheathing should be a non-conductor of electricity. In Fig. 9 the cell is indicated as having a wooden wall 16, provided with a sheathing 17. Extending across the cell are upstanding partitions 18, also made of sheathed wood or of other similar material. These partitions are preferably disposed in an inclined position for a purpose later to be set forth, and the tank will have a plurality of these partitions so that in reality it consists of a number of compartments each of which is a cell. In each of these cells there is an anode support 19 also made of insulating material and having a transverse groove 20 in which the anode is mounted.

As shown in Fig. 6, the anode consists of a slab of metal 21 having upstanding tongues 22, these tongues being spaced so as

to lie opposite the areas 15 on which the metal is to be deposited. Disposed between the tongues are weights 23 which may be of lead, iron, or other suitable metal, preferably covered with an insulating varnish and also provided with handles 24 by means of which they may be slipped into position. The weights are formed with edge flanges 25, 26 which are so disposed that the weights 10 may be slipped down with these flanges engaging the tongues 22 thus holding the weights securely in position. If desired, the end tongues may be provided with terminals 27, 28 by means of which the current may be led to the anodes. Also at the lower edge the anodes are provided with beveled surfaces 28 so that when the anodes are mounted in the grooves 20 in the supporting members in the cells they may be readily swung 20 to and away from the partitions 18.

The separator member which is to lie between the element and the anode and thus keep the anode properly spaced from the element and also transmit the weight of 25 the anode to the element so as to hold the latter in position on its support, is shown in Fig. 2 as consisting of a piece of wood 29 or other similar insulating material. This separator is so formed along the lower edge 30 as to mask those portions of the element which are not to receive the plating and thus the lower edge is cut away as at 30 so as to permit the deposition of the metal on the areas 15. Also on each face of the separator there is a sheet of conducting material 31. This conducting material is one which is substantially insoluble in the electrolyte under ordinary conditions, and for this purpose it is possible to make use of sheet lead, 35 particularly in the ordinary deposition process in which the electrolyte is copper sulphate, since the lead is comparatively insoluble in sulphuric acid. At one end of each face of the separator is a projecting terminal 32 which makes electrical contact with the sheets 31 at 33. It will be seen that these terminals or contacts are mounted symmetrically so that when the separator is reversed the contacts on the faces are always located in the same position. Also the separator has a central projection 34 extending above its upper edge. While I have illustrated the terminals 32 as being in the 40 form of strips of metal, preferably of copper, making contact externally with the metallic faces 31, if desired, the terminals may be in the form of sockets extending into the body of the separator and providing an internal contact with the metallic face. Also, 45 while I have illustrated face plates which cover the entire surface of the separator, it is also possible to make use of projecting contact members, for instance, in the form of strips which extend slightly from the 50 face of the separator and are located so as to contact with the upper edge of the conducting area of the element. These contacts will, therefore, be mounted preferably at the lower edge of the separator and will extend around the edges of the cut-out portions 30.

In the present form of the apparatus I find it is possible to make use of the weight of the anode and the separator to hold the elements in place on their supporting surface 75 and I also find it possible to design the separator in such a way that the upper edge is a gauge by which the elements are properly positioned in the cell. This feature is illustrated in Fig. 10, in which it will be 80 seen that the element designated as 35 is laid in place against the inner surface of the partition 18 with the separator 29 bearing against it and held there by the weight of the anode 21 carrying the weights 23. It 85 will be seen that the separator spaces the anode a considerable distance from the surface of the element and also masks that surface except where the deposit is to occur. The lower edge of the separator which is 90 under the solution therefore serves to define the outline of the deposit. In mounting the elements in place the anode and separator will be swung clear of the partition, the element placed against the surface of the 95 partition and then when the anode and separator are swung back the element will be positioned so that its upper edge 36 lies even with the upper edge 37 of the separator. The separator, in turn, is placed with its 100 edge even with the upper ends of the tongues of the anode and this relation of the parts is such that that portion of the element which is exposed is the portion over which the deposit is to be made. The separator, 105 therefore, not only serves to define the outline of the deposit but its weight plus the weight of the anode acts to hold the element firmly in place during the plating operation. This masking effect of the separator 110 is also brought about by reason of the fact that, as has previously been described, the element is given a conducting coating preferably of graphite and the separator has a metallic contact surface. The terminal 115 through which the plating current is removed from the cell is in contact with this metallic surface and since the metal is a better conductor than the graphite the plating current does not tend to flow above the line of contact of the separator with the graphite. Consequently, the deposit is closely limited to that surface of the element which 120 is exposed below the edge of the separator. The plating current may be introduced 125 into the cell either directly through the anode or else through one of the terminals 32. If the latter method is employed the current will flow into the terminal 32, thence into the plating 31 on the face of the separator. 130

adjacent the anode, thence into the anode and into the cell, and this current then passes through the electrolyte to the conducting coating on the element, thence to the other 5 face plate 31 on the separator and thence out through the other terminal 32.

When this apparatus is in use the operator will place the coated but unplated elements successively in the cells. For this purpose 10 he will grasp the projection 34 on the separator and move the separator and the anode clear of the inclined partition and then place an element against the face of the partition, centering it properly as the separator and 15 anode are moved back against it, or it is also possible to move the anode and separator clear of the partition by means of the car described in my co-pending application previously referred to, this car having a hook by 20 means of which the anodes and separators are moved as the car passes the cells. This method of inserting elements in the cells is repeated until each compartment in the tank has an element in place. Thereafter, when 25 30 the electrodeposition has been carried on for a length of time sufficient to produce a plating of the desired quality and thickness the anodes and separators will be moved clear from the elements, the plated elements withdrawn from the cells and unplated ones inserted. I have found that the density of the electrolyte ordinarily used is such that when 35 the separator is made of wood with its contact area formed of a thin sheet of lead this separator will float in the electrolyte and consequently it is not necessary to provide the separator with clips or some other means by which it may be secured to the anode.

I have found that when the operation of 40 electrodepositing the metal on the elements in the manner above described, is carried on for a considerable length of time a deposit of the metal will take place at the edges 38 of that contact face of the separator which 45 lies against the element. This deposit does not interfere with the deposition on the elements, but as it builds up gradually it tends to extend across the lower face of the separator and, if permitted to build up indefinitely, would eventually reach the anode and 50 thus short circuit the cell. Therefore, it is necessary with the single face separator shown in my previous application, to discontinue the operation of the cells after a 55 certain length of time, to remove the separators and clean off this deposited metal. This interferes, to some extent, with the operation of the apparatus and with the present form of separator the difficulties incidental 60 to the formation of this deposit are easily taken care of. When the deposit has been forming on the edge of the separator for a certain length of time the separator is simply reversed, this operation being carried on 65 when an element is removed and a new one

put in place in the cell. With this reversal an unplated face of the separator now lies against the element and that surface on which the deposit is formed lies against the anode. Depending on which form of terminals have been used, it may be necessary in 70 reversing the separator also to reverse the terminals, but once the cell is in action again the surface containing the deposit will make contact with the anode and the deposit will 75 commence to go into solution. I have found it satisfactory to reverse the separator once every eight to twenty-four hours, depending on the rate of deposition, which will in turn depend on the current density and various 80 other conditions relating to the electrolysis. I have also found that when this reversal is made the accumulated deposit at once begins to dissolve and goes into solution under 85 the conditions described in from one third to one half the time that is required to build it up to a condition which is troublesome. This process of solution of the accumulated metal may be termed a "plating off" process, and 90 the metal plated on the surface of the separator appears to go into solution rapidly and when once the lead is exposed no further solution takes place, since this metal is comparatively insoluble in the electrolyte employed. This simple reversal of the separator, therefore, automatically cleans from it 95 the accumulated deposit and it is not necessary to interrupt the operation of the cell to perform the cleaning, as was previously the case.

In the form of apparatus just described the element is placed against the face of the partition and the separator laid against it and the separator and the element held in place, in turn, by the weight of the element. 105 However, it is possible to make use of these parts in a somewhat different manner and the modified assembly is illustrated in Fig. 12. In that figure the anode 21 used is in the form illustrated in Fig. 6, but is not given the beveled lower edge, nor are the weights 23 mounted upon it. This anode is not moved during the operation of the cell, but lies at all times against the partition 18. The separator 29 is then placed 110 with its edge 39 even with the upper edge 40 of the anode and then the element 35 is laid against the opposite face of the separator with its edge 37 even with the edge 36 115 of the separator. The parts are held in this position by means of a weight 41 which may be made of any desired material, preferably one such as lead or iron with a protected surface. This weight is in the form of a slab which has a beveled lower edge 42, the bevel resting in a channel 43 in a block 44 in the bottom of the cell. With this arrangement when the element is to be removed it is only necessary to swing the weight clear of the element, the separator 120 125 130

always remaining in the position shown. The separator, however, performs the same function as before and when an accumulation of metal takes place along the edge 45 the separator is reversed as has previously been described, and this accumulated deposit is plated off.

It will be seen that the new cell with the improved form of separator may be operated with the greatest efficiency and its operation may continue without interruption for an indefinite period. The anodes go into solution after a considerable length of time and must be replaced, but this replacement is only necessary at long intervals and may be quickly performed so that only one cell is out of commission at a time. Preferably, the operation of the apparatus will be carried on so that the anodes require 20 replacement successively instead of all at once, and in this way this substitution of a new anode for one which has gone almost completely into solution will not interfere with the continuous operation. Also, it will be seen that by making use of a reversible separator the cleaning of the accumulated metal which might have a detrimental effect, is automatically performed and there is no likelihood of any short circuiting of the 25 cell.

While the principles of the invention have been described as put into practice in the manufacture of roofing elements, it will be clear that the process and apparatus 35 above described are capable of use for various other purposes. The apparatus illustrated is in a form which is suitable for the production of three-unit shingles but with slight modifications it may be used for the 40 plating of various other articles. In such other embodiments the shape of the anode and of the separator will depend on the shape of the element and the outline of the area which is to receive the plating, and such other changes in the details of construction will be made as are necessitated by the peculiar circumstances of each case. Also, the use of this reversible separator 45 has been described in connection with what may be termed a stationary anode but in some instances it may be desirable to make use of this separator in a cell in which the anodes and elements are moved along through the cell by means of a conveyor. With such an arrangement a separator of a 55 construction similar to that previously described might be employed and the reversible separator would offer the various advantages which have been pointed out. In either case the use of this reversible separator not only eliminates the cost and delay 60 incidental to the cleaning operation but it also cuts down the cost of installation since with the ordinary separator having but one

contact face it is necessary to provide two 65 complete sets of separators for each set of cells so that one set may be cleaned while the other is in use. This cleaning operation is not only expensive but in many instances would result in damage to the contacts and 70 with the separator designed so that it may be cleaned by the action of the electrolyte the cost of the installation is lowered and the life of the separator is indefinite.

I claim:

1. In an electrolytic cell, the combination of an anode, a cathode and a reversible separator adapted to lie between the anode and the cathode and having conducting contact surfaces engaging the anode and cathode. 80

2. In an electrolytic cell, the combination of an anode, a cathode, and a separator, having similar contact areas of conductive material on its opposite faces, adapted to lie between the anode and cathode with 85 these areas in contact therewith.

3. In an electrolytic cell, the combination of an anode, a support for the article to be plated, and a separator adapted to lie between an article on the support and the 90 anode and having contact areas of conductive material on its opposite faces, adapted to contact with the article and the anode.

4. In an electrolytic cell, the combination of an anode, a support for the article to be plated, and a separator adapted to lie between the anode and an article on the support, and having contact areas on its opposite faces adapted to make contact with the anode and the article, this separator being 100 formed to mask the article and define the shape of the deposit.

5. In an electrolytic cell, the combination of an anode, a support for the article to be plated, and a reversible separator adapted to lie between the anode and an article on the support, this separator having contact areas of conductive material for making 110 contact with the anode and the article and terminals connected with each area. 105

6. In an electrolytic cell, the combination of an anode, a support for the article to be plated, and a separator of insulating material adapted to lie between the anode and the article with portions of its surfaces in contact therewith and having contact areas of conducting material disposed on these surfaces. 115

7. In an electrolytic cell containing an electrolyte, the combination of an anode, a support for the article to be plated, and a separator adapted to lie between the anode and the article and having contact areas to make contact therewith, these contact areas being formed of a material substantially insoluble in the electrolyte. 120

8. In an electrolytic cell containing an

- electrolyte, the combination of an anode, a support for the article to be plated, and a separator adapted to lie between the anode and the article and having contact areas to make contact therewith, these contact areas being formed of a metal substantially insoluble in the electrolyte.
9. In an electrolytic cell, the combination of an anode, a support for the article to be plated and a separator adapted to lie between the anode and the article and having contact areas to make contact therewith, this separator being formed to define the shape of the deposit and having its upper edge serving as a gauge for positioning the article on the support.
10. In an electrolytic cell the combination of an inclined support for an article to be plated, a separator adapted to lie against the article and hold it against movement, this separator having a contact area on one face for making contact with the article and a second contact area on its opposite face, and also having one edge formed to define the shape of the deposit and another edge serving as a gauge for positioning the article on the support, and an anode adapted to lie against the second contact area on the separator.
11. In an electrolytic cell the combination of an inclined support for the article to be plated, a separator having contact areas on either face adapted to lie with one face in contact with the article, a terminal connected with each contact face, and an anode adapted to lie in contact with the second face and to hold the separator against the article.
12. A separator of insulating material for use in an electrolytic cell and having conducting areas, one of which contacts with the anode, the other with the cathode, and terminals connected with these conducting areas, this separator being reversible to permit of the plating off of material accumulating on the conducting area in contact with the cathode.
13. A separator for use in an electrolytic cell comprising a body formed of insulating material having a shape corresponding to that surface of the cathode upon which no deposit is to take place, contacts disposed on either face of the body, and terminals connected with the contacts whereby the plating current may be introduced into the cell through one contact and removed through the other.
14. A separator for use in an electrolytic cell, which compromises a body of insulating material having its opposite faces covered with conductive material and a terminal connected to each face, one of these terminals being disposed at one end of the body and the other at the other end of the body.
15. A separator for use in an electrolytic cell containing a solution of a salt of copper, which comprises a wooden body having a shape corresponding to that surface of the cathode which is not to be plated, lead sheets mounted on opposite faces of the body and terminals mounted in the body and electrically connected with the lead sheets.
16. A separator for use in an electrolytic cell which comprises a body of insulating material having conducting members located on either face, a terminal at each end of the body connected with one of the contact members, and a projection disposed centrally on the upper edge of the body.
17. In a method of electrodeposition, the steps of supporting an insulating separator having conducting contact areas on either face in a cell, maintaining the anode and cathode in contact with these areas, leading plating current into the cell through the anode and out of the cell through the area on the separator in contact with the cathode, and periodically plating off the deposit on the area of the separator in contact with the cathode, by reversing the engagement of the separator areas with the anode and cathode.
18. In a method of electrodeposition, the steps of supporting an insulating separator having conducting contact areas on either face in a cell, maintaining the anode and cathode in contact with these areas, leading plating current into the cell through the area in contact with the anode and out of the cell through the area in contact with the cathode, and periodically reversing the position of the separator to plate off the metal deposited on the area of the separator in contact with the cathode.
19. In a method of electrodeposition, the steps of supporting an insulating separator having conducting contact areas on either face in a cell, maintaining the anode and cathode in contact with these areas, leading plating current into the cell through the anode, and out of the cell through the area in contact with the cathode, and periodically reversing the position of the separator 110 and the electrical connections, whereby the area previously in contact with the cathode and serving as the negative terminal of the cell is placed in contact with the anode.
20. In a method of electrodeposition including the use of an insulating separator having areas of conducting material adapted to lie in contact with the anode and cathode with the plating current passing out of the cell through the area on the cathode side, the step of periodically reversing the position of the separator to plate off the metal deposited on the area on the cathode side of the separator.
21. In a method of electrodeposition in

cluding the use of an insulating separator having areas of conducting material adapted to lie in contact with the anode and cathode and having terminals connected to these areas with the terminal on the cathode side serving as the negative terminal of the cell, the steps of periodically reversing the position of the separator and changing the electrical connections to plate off the metal deposited on the area previously in contact with the cathode.

In testimony whereof I affix my signature.

JULIUS H. GILLIS.
